UNITED STATES PATENT OFFICE.

WILLIAM J. RODGERS, OF LESTERSHIRE, NEW YORK.

DOOR-LATCH.

1,179,041.

Specification of Letters Patent. Patented Apr. 11, 1916.

Application filed January 14, 1916. Serial No. 72,115.

To all whom it may concern:

Be it known that I, WILLIAM J. RODGERS, a citizen of the United States, residing at Lestershire, in the county of Broome and 5 State of New York, have invented certain new and useful Improvements in Door-Latches, of which the following is a specification.

An object of my invention is to provide 10 a latch which may be used upon a screen door and which is so arranged that a knob or pull is presented on the outer side of the door and is so connected with the parts that as a pulling strain is exerted upon said 15 knob, the latch is released and the door will be swung open, the inner latch releasing means being a plate which when pressed will cause the securing latch to be swung from its operative position, further pressure 20 upon the plate causing the door to be opened.

A further object is so to construct the parts that a lock or stop is provided to be set to hold the latch operating means 25 against movement and thus to be secured with the latch set in a locking relation or in a relation in which it is moved to the inoperative position and the door is permitted to have free swinging movement in either 30 direction.

A still further object is to so construct the parts that the device may be used upon a door opening at the right or the left hand and also that the latch releasing pull and 35 the push plate may be disposed either above or below the mounting of the latch proper.

With the above and other objects in view, my invention consists in certain novel features of construction and combinations of 40 parts which will be hereinafter set forth in connection with the accompanying drawings and then more particularly pointed out in the claims.

In the drawings: Figure 1 is a fragmentary view of a portion of the screen door and the door casing with my latch device applied thereto. Fig. 2 is a vertical sectional view on the line 2—2 of Fig. 1. Fig. 3 is a transverse sectional view on the line 50 3—3 of Fig. 1. Fig. 4 is a view similar to Fig. 2 with the parts illustrated in the position which they take when the latch is moved to the inoperative relation. Fig. 5 is a view in perspective of the swinging latch. Fig. 6 is a view in perspective of the latch engaging plate. Fig. 7 is a transverse

sectional view to better illustrate the manner of mounting the latch operating pull. Fig. 8 is a perspective view of the latch operating lever showing the securing means 60 which is mounted in conjunction therewith.

The screen door 1 is hung in the usual manner at one side of the casing to have the free edge thereof swing adjacent the remaining side of the casing 2, and the base 65 plate 3 of the latch is mounted on the free edge of the screen door frame 1, the screws 4 or other suitable fastening means being provided for this purpose. As is shown in Fig. 1, this base plate 3 is preferably made 70 in the form of an elongated rectangle and approximately centrally at one edge of the plate the bearing studs or lugs 5 are provided, these bearing lugs having the bearing 75 openings thereof formed to be in line with the longitudinal extent of the base plate. The bearing brackets 6 and 7 are secured on the base plate 3 at equally spaced apart 80 points above and below the positioning of the lugs 5 and these bearing brackets are so positioned that their bearings are disposed transversely of the base plate 3.

A latch member 8 has the central pivot bearing 9 and one of the arms 10 which will be hereinafter referred to as the locking arm 85 is disposed from the bearing opening in such a relation that it will be received between the bearing lugs 5 as the latch member is mounted by the pin 11 to be capable 90 of swinging movement between these bearing lugs, the arm 12 of this latch member being preferably disposed at an angle from the arm 10 and in such a relation that it will overhang the base plate 3 in line with the bearing brackets 6 and 7. A leaf spring 95 13 is secured on the base plate to engage behind the locking arm 10 of the latch member and thus this latch member is normally held in the position better shown in Fig. 3, where the locking arm 10 thereof projects 100 beyond the extreme edge of the base plate 3 and of the door frame proper to which the base plate is secured.

An operating lever 14 is pivotally mounted by the pin 15 in the bearing bracket 7 105 and at one end has an operating arm 16 which extends beneath the angularly disposed arm 12 of the latch member 8, the remaining end of this operating lever being widened out to form the push plate 17. A 110 latch engaging plate 18 is provided to be secured to the door casing 2 with one end

thereof projecting slightly from the casing in the manner better shown in Fig. 3, and thus as the screen door is swung to the closed position, the latch member 8 will be swung to have its locked arm 10 projecting beyond the edge of the screen door frame and to a position to abut against the latch engaging plate 18 to prevent return swinging movement of the door, the plate 18 acting to bear against the outer edge of the locking arm 10 of the latch member to displace the same from the projecting position against the tension of the spring 13 as the door is brought to the closed relation and this spring 13 exerting the proper tension to again throw the latch member to the operative position. When it is desired to swing the latch member 8 to the released relation this may be accomplished by exerting pressure against the push plate 17 and consequently swinging the operating lever 14 in such a relation that the arm 16 thereof engages beneath the arm 12 of the latch member to swing the same around its pivot and against the tension of the spring 13 to the released position, or where the screen door is to be opened from the outside, the base plate 3 is provided with an opening 19 which is continued on through the door frame 1, a rod 20 being connected with the inner side of the push plate 17 and extended through this opening 19 at the continuation thereof through the door frame and provided on its outer end with the knob 21 which thus forms a door pull 35 which is disposed to be accessible from the outside to permit actuation of the mechanism to release the latch from its engaged position with respect to the latch plate 18.

The stopblocks 22 and 23 are provided on the ends of the base plate 3 beyond the points of mounting of the bracket members 6 and 7, and the metal of the base plate is cored out at 24 and 25 adjacent these stop blocks 22 and 23, this cored out portion being extended beneath the blocks to provide sockets. A locking plate 26, which is better shown in Fig. 8, is mounted on the rear side of the operating lever 14, the headed studs 27 being provided to hold the same against displacement and to permit endwise sliding movement of this plate, and the pins 29 and 30 being mounted on the operating lever 14 to limit movement of the plate in either direction. A tongue 31 is struck up from the metal of the plate 26 and is provided with a hook-shaped foot 32, and as this plate 26 is in its main portion mounted beneath the push plate 17, it is preferable that the end 33 be provided to extend upwardly on either side of the body portion of the operating lever 14 to permit the plate to be grasped and moved in its sliding path to each of its extreme positions.

When it is desired to use the device of my invention as a screen door latch only and to

permit release of the latch member 8 through the medium of the door pull or the push plate, the locking plate 26 will be moved to a relation that it is engaged against the pin 29 and when the parts are in this relation, as is shown in Fig. 4, the operating lever 14 may be given swinging movement within a path to move the latch member 8 against the tension of the spring 13 to the released position, and as the swinging force may be removed from the operating lever, the latch will again be returned to its extended position through the medium of the spring 13. Now, as it is desired to lock the operating lever in such a position that swinging movement thereof to withdraw the latch member against the tension of the spring is permitted, the latch member will be permitted to come to the operative relation after which the locking plate 26 is moved to engage at its lower end against the pin 30 and in this position the foot 32 of the tongue 31 will be disposed above the stop block 33 and swinging movement of the operating lever 14 is stopped. On some occasions it may be desired to release the latch member 8 entirely from the operative relation, and under these circumstances, the operating lever 14 is swung to a position that the arm 16 thereof moves the latch member 8 to the inoperative position and then by moving the locking plate 26 to a relation that the foot 32 is engaged in the cored out opening 25 beneath the stop block 23, the pressure is maintained against the overhanging arm 12 of the latch member 8, and this latch member is permanently secured against outward swinging movement under the tension of the spring 13.

As has been stated, the bearing bracket member 6 is moved on the base plate 3 above the bearing lugs 5 and the stop block 22 and the cored out portion 24 are also above the mounting for the bearing member 8, likewise it is desirable that the opening 34 be provided in a position at the upper end of the base plate 3 corresponding to the disposition of the opening 19. By arranging the parts in this way, the operating lever 14 may be mounted in the bearing bracket 6 to raise the push plate and the door pull, or when the device is fitted to the opposite side of a door frame, the operating lever may be fitted in this bearing to be brought to the same relative disposition as is shown in the present disclosure.

From the foregoing it will be seen that I have provided a door latch and lock device which may be used in the place of the usual hook or other latch or lock generally applied to screen doors, and other like light swinging doors, and which will permit the door to be opened from either the outside or the inside by exerting a force upon a portion of the latch mechanism in a direction

which will cause the door to be moved to the desired open position, and further it will be seen that when the stop plate is moved to a position that the foot thereof engages with 5 one of the stop blocks of the base plate, the latch is securely and positively locked against actuation by movement of the operating lever, this also being true of the setting of the parts when the latch member is swung 10 to be held in the inoperative relation, and while I have herein shown and described only one specific form of the invention, it will be understood that modifications in the construction of the parts and in the combination 15 of the same might be resorted to without departing from the spirit and scope of my invention, and hence I do not wish to be limited to the exact disclosure but only to such points as may be set forth in the 20 claims.

I claim:

1. A door latch comprising a pivotally mounted latch member, an operating lever mounted to be capable of swinging movement to engage with and move said latch to an inoperative relation, a stop, and means 25 adjustably mounted on said lever to be capable of movement to a position to engage with said stop.

2. A door latch comprising a pivotally mounted latch member, an operating lever pivotally mounted to swing against said latch to move the same to an inoperative relation, a block provided with a socket 35 therebeneath, and adjustable means mounted on the lever to be moved to engage in the socket to hold the lever against operative movement.

3. A door latch comprising a base plate, 40 a latch member pivotally mounted on said base plate, a spring bearing against said latch member to normally hold the same in an extended and operative relation, an operating lever pivotally mounted on the base 45 plate to be capable of swinging movement to a relation to engage with the latch member and swing the same against the tension of the spring to the inoperative relation, a stop block carried by the base plate, and 50 means carried by the operating lever to be moved to a relation to engage with the stop block to hold the lever against swinging movement.

4. A door latch comprising a base plate, 55 a latch member pivotally mounted on said plate, a spring acting to normally hold said latch member in a relation that it is extended to an operative position, an operating lever pivotally mounted on said base plate 60 to actuate said latch member when said lever is moved and provided with portions by which movement is transmitted thereto from the inside and the outside of the door, said base plate provided with a socket, and means 65 carried by the operating lever to be en-

gaged in said socket as the lever is moved to a position to swing the latch member to the inoperative relation to thus hold the parts in this relation.

5. A door latch comprising a base plate to be secured to a door frame adjacent the edge thereof, a latch engaging plate to be secured to the door casing, a latch member pivotally mounted on the base plate, a spring acting to normally hold said latch member swung to a relation to engage with the latch plate, an operating lever pivotally mounted on said base plate to engage with said latch member to swing the same to the inoperative relation as the operating lever 70 is moved, a stop block carried by the base plate, said plate provided with a cored out socket adjacent the stop block, and stop means carried by said operating lever to be engaged with the stop block to hold the operating lever against movement in one direction and to be engaged in the socket to retain the same against swinging movement in the opposite direction.

6. A door latch comprising a base plate 90 to be secured to the door frame adjacent the swinging edge thereof, a latch engaging plate to be mounted to the door casing, a latch pivotally mounted on said base plate, a spring engaging with the said latch member to normally hold the same in a relation to abut against the latch engaging plate carried by the casing, an operating lever pivotally mounted on the base plate to have an extension arm thereof in a relation to 95 engage with the latch member as the lever is swung, a push plate provided on the opposite end of the operating lever, means connected with said operating lever to be extended through the door to permit actuation thereof from the outside, a stop block mounted on the base plate, a cored out socket provided adjacent the stop block, and a plate slidably mounted on said operating lever and provided with a foot to engage 100 against the stop to hold the lever in one of its operative relations and to be engaged in the socket to hold the lever in a second extreme position.

7. A door latch comprising an elongated base plate to be secured to the door frame adjacent one end thereof, a latch engaging plate to be secured to the door casing, a latch member pivotally mounted on said base plate at the approximate longitudinal 115 center thereof, bearings provided on the base plate at each side of the mounting of the latch member, a spring to normally hold the latch member swung to a relation to engage with the latch plate, an operating lever pivotally mounted in one of said bearings carried by the base plate, and provided with an extension arm to engage with the latch member, a push plate provided on the end of the operating lever, a door pull con- 120 125 130

4
nected with said operating lever and ex-
tended through the door to permit actua-
tion of the operating lever from the outside,
stop blocks positioned on each end of the
base plate beyond the mounting of the bear-
ings, said plate provided with cored out
sockets adjacent said stop blocks, a locking
plate slidably mounted on said operating
lever and provided with a foot to be en-
gaged against one of said stop blocks to
hold the operating lever against movement
to engage the latch member and to be fitted
in the sockets to hold the operating lever
in a relation to restrain the latch member

in the inoperative relation, and means to 15
limit movement of said locking plate, the
plurality of bearings and stop blocks and
the central mounting of the latch member
permitting the operating lever to be fitted
at either end of the base plate and thus 20
adapting the device to be fitted to either side
of a door.

In testimony whereof I affix my signature
in presence of two witnesses.

WILLIAM J. RODGERS.
